UNITED STATES PATENT OFFICE.

HORACE L. KENT, OF BROOKLYN, NEW YORK.

LOUD SPEAKER.

Application filed May 17, 1924. Serial No. 712,922.

My invention relates to what is sometimes termed a reproducer or receiver. The main object is to provide a simple and reliable mechanism for reproducing faithfully words and music so that they can be heard at a distance and yet without the use of a horn.

In carrying out the invention I employ a large special diaphragm and sounding board construction. The diaphragm is operated in any suitable manner either electro-magnetically or by what is termed a phonograph record. The preferred form is illustrated in the accompanying drawing.

Fig. 1 is a front view of parts embodying improvements of my invention on a small scale.

Fig. 2 is a sectional view of the same, full sized.

Fig. 3 is an enlarged fragmentary section showing the connection between the diaphragm and the operating member.

Fig. 4 is a section on line 4-4, Fig. 1. In the particular example shown the energizing coil 5 is supported at one pole of a magnet 6, which is supported by a bracket 7. The armature 8 is pivoted to the other pole of the magnet and adapted to be adjusted and vibrated in a manner common in telephone receivers.

The center of the diaphragm 9 is connected to the armature 8 by a rod or wire 10. The outer edge or rim of the diaphragm is preferably reinforced by a ring 11, which is supported preferably by the outer edge of the box 12. For convenience in manufacture, transportation and use, the box is preferably provided with a bottom 13 to which the brackets 7 are secured. The diaphragm should be quite large in diameter in order to produce the best results, for instance, eight inches in diameter or even larger.

The sleeve 14 and the washer 15 are secured to the diaphragm 9. The bushing 16 is screwed on to the end of the wire 10 and held in position by the clamp nut 17, and has an index pointer 18 extending from one edge, and movable over a scale or dial on the diaphragm. A stop 19 limits the rotation of the pointer 18. The screw 20 serves to lock the bushing 16 in the sleeve 14. When the armature is vibrated in the usual manner it will transmit motion to the diaphragm

9 through the wire 10, bushing 16, and sleeve 14.

Immediately back of the diaphragm 9 is a sounding board 21 which is preferably supported by the outer edge of the box 12 either directly or indirectly. This sounding board 21 has a reinforcing rim or ring 22 and the rings 11 and 22 are secured together by a series of screws 23. I have found that very satisfactory results can be obtained by the use of a diaphragm made of bakelite or waterproof fibre approximately $\frac{1}{8}$ of an inch thick, and a sounding board of wood approximately $\frac{3}{8}$ of an inch thick. The diaphragm and the sounding board must be secured close together and properly adjusted with respect to each other to produce the desired results, for instance, they may be spaced $\frac{1}{16}$ of an inch apart. The spacing can be effected in any suitable manner, as for instance, by means of washers 24. When these washers are of definite thickness, of course, very little adjustment is possible, but by making the washers somewhat resilient it is possible to adjust the diaphragm and sounding board with respect to each other so as to obtain material modification in the volume and quality of reproduction. I may also, in some cases prefer to employ a post or sound transmitting member 25 clamped between the diaphragm and the sounding board near the center so as to couple the two members together and increase the volume of tone.

Preferably there is an opening around the major part of the periphery of the space between the diaphragm and the sounding board as shown at 26 in Fig. 4 through which the air vibrations may escape and thus out through the screen 27 at the top. The sides of the box may also have screened openings as at 28 if desired.

While I am not able to fully explain the theory of operation of this invention, experience has shown that it is possible to obtain by it quite remarkable effects of clarity and smoothness of reproduction throughout the widest range of pitch and character of sound. Tones which become blatant and unnatural when thrown from a horn are sounded clearly and naturally by the combined diaphragm and sounding board.

I claim:

1. A loud speaker comprising a diaphragm of upwards of 9 inches in diameter, a sounding board of approximately the same diameter, and a series of washers interposed between the rims of said diaphragm and said sounding board, and means for varying the space between said members.
2. A loud speaker comprising a diaphragm at least 8 inches in diameter and approximately $\frac{1}{4}$ of an inch thick, a sounding board $\frac{3}{8}$ of an inch thick spaced approxi-
- 5 mately $\frac{1}{8}$ of an inch away from the diaphragm, and means for vibrating said diaphragm.
3. A loud speaker comprising a diaphragm of bakelite at least 8 inches in diameter, a wooden sounding board secured close thereto and of approximately the same diameter, and means for vibrating said diaphragm.

HORACE L. KENT.
